UNITED STATES PATENT OFFICE.

HENRY WEBER, OF CHICAGO, ILLINOIS, ASSIGNOR TO LATHAM MACHINERY COMPANY,
OF CHICAGO, ILLINOIS, A CORPORATION OF ILLINOIS.

STAPLING-MACHINE.

1,132,990.

Specification of Letters Patent. Patented Mar. 23, 1915.

Application filed May 7, 1914. Serial No. 836,856.

To all whom it may concern:

Be it known that I, HENRY WEBER, a citizen of the United States, residing at Chicago, in the county of Cook and State of Illinois, have invented certain new and useful Improvements in Stapling-Machines, of which the following is a specification.

My invention relates to stapling machines and has for its primary object the provision 10 of an improved stapling machine which shall have improved means for reciprocating the anvil thereof into and out of the path of movement of the driver.

With the above and other objects in view, 15 this invention consists substantially in the combination, arrangement and construction of parts all as hereinafter described, shown in the accompanying drawings, which form a part of this specification and illustrate the 20 preferred embodiment of my invention, and more particularly set forth in the subjoined claims.

In the drawings: Figure 1 is a front elevation of a stapling machine embodying my 25 invention. Fig. 2 is a fragmentary view of the same, with a supporter plate removed to disclose certain parts. Fig. 3 is a perspective view of an anvil shown in front end elevation in Fig. 2, together with parts 30 which assist in its reciprocation. Fig. 4 is a section taken approximately on line 4—4 of Fig. 1. Fig. 5 is a section similar to Fig. 4, showing a different position of the parts. Fig. 6 is a section taken approximately on 35 line 6—6 of Fig. 4.

In Fig. 1 is illustrated a type of stapling head well known in the prior art and having a cammed wheel generally indicated by reference numeral 10, which operates feeding 40 mechanism generally indicated at 11, a cutter 12 (see Fig. 6), a former 13, and a driver 14. In this type of stapling head an anvil is employed, provided with a slotted forward end which receives one or more wires and 45 which is flattened on its sides to fit within the former 13, which, descending about said flattened sides, bends the wire held in the flattened slotted head of the anvil into staples. Formerly, in this type of stapling 50 head the driver 14 was adapted by its descent to move the anvil backwardly by engagement with a beveled surface upon the upper side of the forward end of the anvil, and to remove the anvil from its path of de-

scent, the driver pushing the formed staple 55 or staples ahead of it through the work and against a clench block below the work. In my present invention I show for convenience a stapling head adapted to form and drive a plurality of staples, though my invention 60 is applicable to a machine constructed for the operation of a single staple at a time. In the present invention reference numeral 15 (see Figs. 2 to 6 inclusive) indicates generally the anvil of my stapling machine. 65 This anvil is provided at its forward end with a horizontal slot 16, is beveled at approximately an angle of forty-five degrees from the vertical upon its forward end and above the slot 16, as at 17, and is rounded 70 off as at 18 for engagement with a staple support 19, shown in Figs. 4, 5, and 6. The frame plate of my invention is indicated at 20, and in this plate is cut an approximately vertical channel 21, within which is suspended 75 a link 22, shown in perspective in Fig. 3, in side elevation in Figs. 4 and 5, and partly in cross section and partly in plan view in Fig. 6. At its upper end and upon its forward face the link 22 is provided with a stop 80 23, from which extends forwardly a shaft 24 forming a bearing for a roller 25. A cam 26, formed upon the cammed plate 10, cooperates with the roller 25 to impart motion to the link 22. The link is suspended 85 within the channel 21 by means of a coil spring 27 (see Figs. 4, 5, and 6), bearing preferably at its upper end a core 38 having a block 39 for engagement with the stop 23. At its lower end the link 22 is bifurcated, 90 forming spaced link leaves 28, each of which is provided with a straight link slot 29, the link slots 29 registering opposite each other and extending preferably at an angle of forty-five degrees from the vertical. The 95 rearward end of the anvil 15 is reduced as at 15^a (see Figs. 3 and 6) sufficiently to move freely between the link leaves 28. A link block 30 passes through the reduced end 15^a of the anvil and at each of its ends engages 100 one of the slots 29. The anvil is journaled as at 31 for horizontal reciprocation in the frame plate 20. A guide plate 32 (see Figs. 4, 5, and 6) is fastened to the rearward surface of the frame plate 20 and spans the 105 channel 21, thus securing the link 22 within the channel.

In the operation of my invention the feed-

ing mechanism generally indicated at 11 feed staple material into the slot 16 of the anvil, following which the former 13 descends about the flattened sides of the anvil, 5 bending the staple material into staples. Upon this formation of the staples the driver 14 begins to descend upon the staples and during its descent contact of the cam 26 with the roller 25 moves the link 22 downwardly from the position shown in Fig. 4 10 to that shown in Fig. 5, this downward movement of the link being made against the force of the spring 27. As the link moves downwardly the link block 30 is 15 forced backwardly, drawing backward with it the anvil 15, the anvil retreating a distance sufficient to clear the path of descent of the driver 14. The anvil being thus withdrawn from the path of descent of the 20 driver, the driver passes on, pushing the staples before it and setting them into the work. Preferably, the shape of the cam 26 is such that when the staples have been set into the work by the driver, the cam 26, as 25 it rotates, rises from the position shown in Fig. 5, clearing the roller 25, and allowing the spring 27 to move the link 22 upwardly. This upward movement of the link 22 is momentarily arrested, however, by the driver 30 14, which, during its ascent, obstructs the forward movement of the anvil until the lower end of the driver has passed the slot 16, whereupon the spring member 27, by forcing the link 22 upwardly, snaps the 35 anvil forward into the position shown in Fig. 4.

In the accompanying drawings and in the foregoing description is set forth the preferred embodiment of my invention, but it is 40 obvious that one skilled in the art may make modifications thereof without departing from the spirit of the invention.

I claim:

1. In a stapling machine having an anvil 45 and a driver, the combination of means independent of the driver for moving the anvil comprising a reciprocating link having slots obliquely positioned with relation to the anvil, an extension upon the anvil overlapping said slots, and a link block engaging and movable in said slots and fixed to said extension.

2. In a stapling machine having an anvil and a driver, the combination of means independent of the driver for moving the anvil comprising a link mounted in the machine for vertical reciprocation, a bearing in the machine in which the anvil is mounted for horizontal reciprocation, said link having 55 slots obliquely positioned with respect to the line of desired movement of the anvil, a rearward extension upon the anvil overlapping said slots, and a link block engaging and movable in said slots and fixed to said 60 extension.

3. In a stapling machine, the combination of a frame therefor, a vertically extending channel in said frame, an anvil movably mounted in the frame, a link movably positioned for vertical reciprocation in said channel, bifurcated at its lower end, and having oblique slots registering with each other formed in the bifurcations, an extension upon the anvil movable between the bifurcations of the link, a link block engaging and movable in said slots and fixed to said extension, a spring member upon which said link is suspended and normally maintaining the link adjacent the upper end of said channel, and a rotating cam adapted to 70 contact with the link and move it downwardly in said channel against the pressure of the spring member.

4. The combination with a stapling head, including a former and a driver, and means for imparting a reciprocatory movement thereto, of an anvil movable across the path of movement of the driver and former aforesaid, and a connection between the means for operating the driver and former and said anvil, comprising a link having oblique 75 slots therein for coöperation with the anvil aforesaid.

5. The combination with a stapling head, including a driver and a former and a cam 95 for imparting a reciprocatory movement thereto, of an anvil mounted for reciprocation across the paths of movement of said driver and said former, and a link operable by said cam, and provided with oblique slots 100 in its lower terminal for engagement with the outer end of said anvil.

6. The combination with a stapling head, including a driver and a former and a cam 105 for reciprocating said driver and said former, of an anvil mounted for reciprocation across the paths of movement of said driver and former, a link block secured transversely in the outer end of said anvil, a link spanning the outer end of said anvil 110 and provided with oblique slots therein in which is received the link block aforesaid, an operative connection between the outer end of said link and the cam aforesaid, and means constantly tending to maintain the 115 said connection.

7. The combination with a stapling head including a former and a driver and means for imparting a reciprocatory movement thereto, of an anvil movable across the path 120 of movement of said former, and a connection between the means for operating the driver and former and said anvil comprising a link having oblique slots therein for coöperating with the anvil aforesaid.

8. The combination with a stapling head including a former and a driver, and means for imparting a reciprocatory movement thereto, of an anvil movable across the path 125 of movement of the driver and former aforesaid.

said, a connection between the means for operating the driver and former and said anvil comprising a link having oblique slots therein for coöperating with said anvil, and
5 means for moving said link independently of said former.

In testimony whereof I have signed my

name to this specification, in the presence of two subscribing witnesses, on this 5th day of May, A. D. 1914.

HENRY WEBER.
